UNITED STATES PATENT OFFICE.

GEORGE BATY AND ROBERT M. RYAN, OF NEW YORK, N. Y.

SEMIPERMANENT PHONOGRAPH NEEDLE.

Application filed May 15, 1923. Serial No. 639,049.

The object of our invention is to provide a needle of this class and character which may be used repeatedly with little or no alteration and which will last indefinitely, practically eliminate scratching, and accurately render the sounds of the phonograph to which it is attached. This and other objects are accomplished by our invention, one embodiment of which is hereinafter more particularly set forth.

For a more detailed description of our invention, reference is to be had to the accompanying drawings, forming a part hereof, in which

Figure 1 is a side elevation of a needle embodying our invention, a part being broken away to reveal the structure.

Figure 2 is a sectional view, taken on the line 2—2 of Figure 1, looking in the direction of the arrows.

Figure 3 is a perspective view of this needle, and

Figure 4 shows a needle in place in an ordinary phonograph.

Figure 5 shows a modification.

Throughout the various views of the drawings, similar reference characters designate similar parts.

Our improved needle 1 comprises a holder 2 and a wire 3 which is adapted to enter a groove in a record 4 which rests on a turn table 5. The holder 2 has a shank 6 which is adapted to be fixed in an ordinary needle holder 7 of a phonograph 8 in the conventional way. In the preferred embodiment of our invention, this shank 6 terminates at a shoulder or enlarged portion 9 which is preferably made rectangular in cross section and is provided at its free end with a downwardly extending point 10 which extends at any suitable angle, say 45 degrees, and terminates in a round nose 11. This point 10 is provided with a suitable perforation, at or near its middle point, through which is passed a pivot pin 12 which engages the up-turned ears 13 on each side of the end 10 and extend from the U trough 14 which runs parallel to the shank 6, or substantially so, in the usual embodiment of my invention, although of course this is not essential and may be varied if desired. This U trough 14 is slotted to receive a leaf spring 15 that is adapted to rub against the part 9.

The function of this leaf spring 15 is to

separate the parts 14 and 9 so that the wire 3 is clamped in the hollow of the U by the nose 11 of the end 10.

This wire 3 has one end fixed to a guide 16 so that this guide may be slid on the U 14 and thereby shift the wire 3 in the direction of its length. This wire cannot be so shifted unless the parts 9 and 14 are brought towards each other so as to free the nose 11 from the wire, as indicated in dotted lines in Fig. 1, at which time this adjustment may take place. Once this adjustment has taken place, the parts 14 and 9 are allowed to separate on the pivot 12 as an axis and then the nose 11 will clamp the wire 3 at the desired position. This adjustment must take place from time to time according to the wear on the wire when in use and the loudness of sound to be produced. It can be adjusted to suit the desires of the person playing the instrument with great ease and facility, making the tone either loud or soft, as desired.

In the preferred embodiment of our invention, the wire 3 is made of gold, but this may be varied, if desired. This wire is made small enough to fit in the ordinary groove of a phonograph record and it wears to fit very readily and thereafter will last a long time, say several hours, without adjustment or replacement of any kind whatsoever. If the needle 1 be removed from the phonograph 8 for the purposes of adjustment, it can easily be replaced without any shifting because it is easy to keep the parts 14 and 9 in the same vertical plane, and the needle 3 has no chance to turn on its axis when adjusted. From this it is apparent that the needle can be used several times and at different times and after removal and insertion it will always present the same true edge to the record.

In the embodiment of our invention shown in Figure 5, the structure is the same as before, except that the holder 2 has an end 10 which is pivotally connected to the part 9 by means of ears 17 and a clamping screw 18 so that the angle between the parts 9 and 14 may be varied, as desired, so that this needle may have a wide range of adjustment, if desired, and be made to fit any peculiar phonograph.

In view of the foregoing, the use of our improved needle will be readily understood.

It is placed in a phonograph in the usual way and used in the conventional manner, and from time to time removed and adjusted, as desired, and it can be adjusted without removal. In any position, a great many records may be played one after another without changing the needle.

While we have shown and described one embodiment of our invention, it is obvious that it is not restricted thereto, but that it is broad enough to cover all structures that come within the scope of the annexed claims.

Having thus described our invention, what we claim is:

15 1. A phonograph needle composed of a holder and a wire stylus, the holder having two parts normally in parallel relation and pivotally connected together and swinging in the same plane, the two parts being so connected that the wire may be automatically clamped between them.

20 2. A phonograph needle composed of a holder and a wire stylus, the holder being composed of two parts with engaging ends 25 adapted to clamp a wire between them and a spring tending to separate said parts,

whereby the wire may be clamped automatically.

3. A phonograph needle composed of a holder and a wire stylus, the holder having two parts pivotally connected and in substantially parallel relation, one of said parts entering the needle holder of a phonograph and the other of said parts holding said wire.

35 4. A phonograph needle composed of a holder and a wire stylus therein, the holder having articulated parts so that the wire may be placed at any of several angles and means for causing the holder to automatically clamp the wire.

40 5. A holder for a wire stylus, said holder composed of a U piece with extending ears pivotally connected to an end of another part of the holder, and a spring engaging the two parts and separating them, whereby 45 said wire may be clamped between them.

Signed at the city of New York, county of Kings and State of New York.

GEORGE BATY.
ROBERT M. RYAN.
